UNITED STATES PATENT OFFICE.

HARRY A. BROOKS, OF GLENDALE, CALIFORNIA, ASSIGNOR TO CHARLES A. DEAL, OF LOS ANGELES, CALIFORNIA, AND MARVIN E. COX, OF SAN DIEGO, CALIFORNIA.

PNEUMATIC MOTOR-STARTING APPARATUS.

1,148,888.

Specification of Letters Patent.

Patented Aug. 3, 1915.

Application filed April 6, 1914. Serial No. 830,094.

To all whom it may concern:

Be it known that I, HARRY A. BROOKS, a subject of the King of Great Britain, residing at Glendale, county of Los Angeles, State of California, have invented a certain new and useful Pneumatic Motor-Starting Apparatus; and I do hereby declare the following to be a full, clear, and exact description of the invention, such as will enable others skilled in the art to which it appertains to make and use the same.

This invention relates to pneumatic motor starting apparatus, and it may be said to consist in the provision of the novel and advantageous features and in the novel and improved construction, arrangement, and combination of parts and devices as will be apparent from the description and claims which follow hereinafter.

Objects of the invention are to provide a novel and improved apparatus of the class specified which is simple and compact in construction, strong and durable, easily applied to existing motors, light in weight, economical to manufacture, install, and maintain, easy and convenient to use, positive and effective in operation, freed from the motor shaft when it is not in operation, and by the use of which is avoided all danger of injury in case of back-firing or rotation of the motor shaft in a reverse direction.

Other objects and the advantages of the invention will be apparent to those skilled in the art from a consideration of the following description of the preferred form of construction embodying the invention, taken in connection with the accompanying drawings in which—

Figure 1 is a front elevational view of the apparatus, with parts omitted and parts in section; Fig. 2 is a partly broken front elevational view of the apparatus, with some parts in changed position and other parts in section; Fig. 3 is an elevational end view of a portion of the apparatus; Fig. 4 is a cross-sectional view of the apparatus, with parts omitted, taken on the line 4—4 of Fig. 2; Fig. 5 is a cross-sectional view of the apparatus, with parts omitted and parts in changed position, taken on the line 5—5 of Fig. 2; Fig. 6 is a perspective view of the crank, with curved wedges shown in dotted

lines; and Fig. 7 is a partly broken and sectional view of the barostat disks.

The frame 10 has thereon a preferably integral pneumatic motor cylinder 11 which has one end thereof closed by a suitable head 12 and has its other end open. A valve 13 is arranged at the head end of the cylinder 11 and preferably comprises a closed cylinder 14 and an oscillatable member 15 which is provided with admission and exhaust ports 16 and 17 which are adapted to register with the port 18 in the cylinder 11. In the cylinder 11 is arranged a piston 19 having thereon piston rings 20 and provided with a wrist pin 21 to which is pivotally connected one end of a link 22 which latter has its other end pivotally connected to one end of a crank 23 which extends through a slot 24 in the open end portion of the cylinder 11. The other end portion of the crank 23 is formed with a sleeve 25 provided with an extension 26 of increased diameter. A coil spring 27 is arranged on the extension 26 and has one end thereof secured to the extension and has the other end 28 thereof secured to the frame 10. The spring 27 is put under tension during the outward stroke of the piston 19 and is adapted to return the piston to the inner or head end of the cylinder 11—the latter preferably being inclined downwardly toward the head end to facilitate movement of the piston by the spring. Outwardly-inclined curved surfaces 29 are provided on the sleeve 25 and have slidably arranged thereon curved blocks or wedges 30 which are of less length than the surfaces 29 and diverge from one end to the other. The large end portions of the wedges 30 are disposed on the small end portions of the surfaces, and straps 31 are pivotally connected to the large and small end portions of adjacent wedges 30. A cage 32 on the extension 26 bears on balls 33 which are arranged in raceways 34 supported by an annular flange 35 which latter is preferably formed integral with the frame 10. In a socket 36 on the crank 23 is arranged a spring 37 which is adapted to press against a projection 38 on the rear of one of the wedges 30 to move the wedges 30 on the surfaces 29 outwardly into frictional contact with the annular offset 39' of a flange 39 which may be formed on or secured

to the shaft 40 which latter passes freely through the flange 35 and sleeve 25 and may be suitably connected to the shaft, not shown, of an internal combustion engine, 5 not shown.

The frame 10 may have thereon lugs 41 or other suitable means whereby it may be attached to the front end of the frame of an automobile. A ball bearing 42 for the 10 shaft 40 is preferably fitted in a circular recess formed in a bracket 43 which may be secured by cap screws 44 to the frame 10 and to a lug 45 on the cylinder 11. A pin 46 on the shaft 40 permits of cranking the 15 shaft manually when desired. A dog 47 is adapted to engage with a projection 48 on the rear side of one of the wedges 30 to hold the wedges inwardly against the pressure of the spring 37 and out of contact with the offset 39'; said dog having thereon a pivot 49, bearing in the bracket 43, and an arm 50 to which is attached a wire 51 which passes through a tube 52 which latter may be secured by a clamping 20 block 53 and screws 54 to a lug 55 on the cylinder 11. Interposed between the lug 55 and arm 50 is a coil spring 56 which is compressed when the wire 51 is pulled to disengage the dog 47 from the projection 48, 25 and is adapted to cause reengagement of the dog 47 with the projection 48 when the pull on the wire ceases.

The oscillatable member 15 of the valve 13 is carried by a shaft 57 which has one end thereof mounted in a bearing 58 in the rear end of the cylinder 14 and has the other end portion thereof passing through the head 59 of the cylinder and connected to an arm 60 which latter is provided with a counterweight 61 at one end thereof and with an offset portion 62 at the other end thereof. In order that the oscillation of the member 15 may be easily effected notwithstanding the pressure of the air in the cylinder 14, 40 the shaft 57 has a substantially rectangular portion thereof disposed between depending flanges 63 on the member 15, and pins 64 are passed through the flanges 63 and through elongated openings 65 in the shaft 57. A lever 66 has one end thereof mounted on a pivot 67 which passes through the offset portion 62 and is secured by the jam nut 68. At a point between the ends of the lever 66 is attached one end of a coil spring 69 which has its other end suitably attached to the frame 10. The spring 69 holds the lever 66 in contact with a grooved roller 70 which is mounted on a pivot 71 suitably mounted on the frame 10. A projection 71 45 on the sleeve 25 is adapted to bear against the roller 72 on the rear side of the lever 66 to actuate the lever to cause movement of the oscillatable member 15 to the exhaust position, and said projection 71 is adapted to engage with a projection 73 at the end

of the lever 66 and, assisted by the spring 69, actuate the lever to cause movement of the member 15 to bring the admission port 16 into registry with the port 18. A hump 74 on the lever 66 is adapted to bear 70 against the roller 70 to cause the spring 69 to act on the lever 66 with a snap action and hold the lever 66 from movement after said lever has been moved by the projection 71 to move the member 15 to the admission or 75 exhaust position. A stop 75 is secured to the frame 10 by cap screws 76 and is adapted to engage the projection 48 to move the wedges 30 inwardly to cause disengagement of the wedges with the annular offset 39' 80 should the engine, not shown, start to operate the shaft 40 in a reverse direction.

An air compressor adapted to be operated by the shaft 40 is mounted on the frame 10 and has its operation controlled through 85 the action of a barostat. The air compressor preferably consists of a cylinder 76 having one end thereof open and having a head 77 screwed in the other end thereof. A spring-pressed valve 77' is arranged in 90 the cylinder 76 adjacent to the head 77, and a hollow piston 78 is arranged in the cylinder 76 which piston has at its inner end a puppet valve 79 and has a port 80 at its outer end. An oil duct 78' and an air pipe 95 79' may be connected to the cylinder 76 in any suitable manner. The piston 78 has thereon an extension 81 which is slidably mounted on an extension 82 on the cylinder 76 and provided with a slot 83 for the reception of one end portion of a retracting spring 84 which latter has its other end suitably secured to the frame 10.

A link 85 has one end portion thereof formed bifurcated and mounted on a pivot 86 on the extension 81, and it has the other end 87 thereof formed to contact with an eccentric 88 which is mounted fast on the shaft 40. The cylinder 76 is mounted on a bracket 89 on the frame 10, and said bracket has, on the upper part thereof, inclined conical points 90 which are fitted in conical recesses 91 which latter are larger in size than the conical points 90 and are formed in the inclined end portions at the upper part of a bar 92 which bar is pressed at its lower part by a spring 93 extending into a socket 94 screwed into the bracket 89. The pressure of the spring 93 may be adjusted by turning the socket 94. The bar 110 92 has thereon an arm 95 provided with a hook 96 which is adapted to fit on a projection 97 on the rear side of the bifurcated end of the link 85. A casing preferably consisting of a hollow bottom part 98 suitably secured to the frame 10 and a hollow top part 99 screwed thereon has arranged thereon a plurality of spaced corrugated hollow disks 100. Near their center the top and bottom of adjacent disks 100 are joined together by cir- 115 120 125 130

cular walls 101. A stem 102 suitably secured to the upper of the disks 100 extends freely into a recess 103 at the top of the casing, and a hollow nipple 104 is suitably affixed to the lower of the disks 100 and extends through and is secured to the bottom part 98 of the casing by means of a hollow nut 105. A rod 106 extends freely through the central portion of the nut 105, 10 nipple 104, and the disks 100. The rod 106 is formed with a conical point 107 at one end thereof which is fitted in a conical recess 108 of larger size formed at the bottom of the stem 102, and with a conical point 109 at the other end thereof which is fitted in a conical recess 110 of larger size formed at the top of the bar 92. Air from a suitable storage tank may pass to the casing through the port 111 and pipe 112 connected therewith. The storage tank is not shown but it will be understood that when the apparatus is applied on an automobile the tank may be disposed in any convenient position on the automobile. In the raised position of the link 85, the end 87 may bear against a lug 113 on the frame 10, and a shoulder 114 on the front side of the bifurcated end of said lever may bear against a projection 115. 20 In operation—air under pressure having been admitted to the valve cylinder 14 through a suitable valve, not shown, in the pipe 116 which is connected to the storage tank—the wire 51 is pulled to effect disengagement of the dog 47 with the projection 48 so that the spring 37 may act to move the wedges 30 outwardly into frictional contact with the offset 39' of the flange 39, whereupon the air passing through the ports 35 16 and 18 drives the piston 19 and thereby effects a movement of the crank 23 to cause the sleeve 25 to turn and thereby jam the wedges 30 between the surfaces 29 and the offset 39' so that the latter turns with the sleeve 25 and causes the shaft 40 to turn. Should the shaft 40 while it is being turned by the crank shaft its motor to operate, the faster movement of the offset 39' in a direction opposite to that of the sleeve 25 will 40 cause the wedges 30 to move inwardly and operatively disconnect the offset 39' from the sleeve 25. Should the motor start to drive the shaft 40 in a reverse direction, the projection 48 will be moved to engage the stop 75 and cause the wedges 30 to move inwardly and thus operatively disconnect the sleeve 25 from the offset 39'. When the piston 19 has completed about one half of its working stroke the projection 71 engages with the roller 72 on the lever 66 and moves the lever to effect a movement of the member 15 of the valve 13 to close the port 18 to permit expansion of the air in the cylinder 11 to drive the piston 19 to the end of the stroke. At the time the piston

reaches the end of the stroke, the member 15 will have been moved to have the exhaust port 17 in registry with the port 18 so that the air may be exhausted from the cylinder 11 by way of the ports 17 and 18 and pipe 117 when the spring 27 acts to return the piston 19 to the head end of the cylinder 11. On the return stroke of the piston 19 by the spring 27 the latter acts to turn the sleeve 25 so that the wedges 30 are moved inwardly and the projection 71 is caused to engage the projection 73 on the lever 66 and move the latter to effect a movement of the valve member 15 which brings the ports 16 and 18 into registry at the end of the return stroke of the piston 19. The operation of the crank 23 by the piston 19 is continued until the motor starts, whereupon the wire 51 being no longer pulled the spring 56 acts to cause a movement of the dog 47 into engagement with the projection 48 and the starting apparatus is freed from operative connection with the motor shaft 40. 25

When the shaft 40 is driven by its motor, not shown, the eccentric 88 is adapted to move the link 85 and cause the piston 78 to compress air admitted through the valve 79 and force the compressed air through the valve 77' and through the pipe 79' to the storage tank. The compressed air exerts a pressure on the disks 100 in the casing and causes the disks to crowd together and thereby cause a downward pressure on the rod 106. When the pressure of the air reaches a predetermined amount, the pressure of the rod 106 on the bar 92 is such that the hook 96 engages the projection 97 and the spring 93 acts on the bar 92 to have the arm 95 move the lever 85 to raised position. When the pressure of the air in the casing falls, the disks 100 spread apart and exert less pressure on the rod 106 and hence on the bar 92 so that the spring 93 may act to cause a movement of the arm 95 to disengage the hook 96 from the projection 97, whereupon the pin 118 on the flange 39 is adapted to engage the projection 119 on the link 85 to move the latter from its raised position to operative connection with the eccentric 88. While the end 87 of the link 85 is in contact with the eccentric 88, the projection 118 is radially nearer to the shaft 40 and misses the projection 119 when the shaft 40 is rotated by its motor. 100

While one form of the construction embodying the invention has been particularly illustrated and described, many changes and modifications thereof will occur to those skilled in the art—wherefore the right is reserved to all such changes and modifications as do not depart from the spirit and scope of the invention as defined in the appended claims. 115

I claim:

1. In apparatus of the class specified, the 120

combination of a frame, a motor thereon, a crank formed with a sleeve rotatively mounted on the frame and operatively connected with the piston of said motor, a shaft having a flange thereon and passing through said sleeve, wedges on the sleeve adapted to frictionally engage with said flange, a retracting spring attached to the sleeve and to the frame, and means operatively connected with the sleeve and with the valve of said motor for operating the valve.

2. In apparatus of the class specified, the combination of a frame, a motor thereon, a crank formed with a sleeve rotatively mounted on the frame and operatively connected with the piston of said motor, a shaft having a flange thereon and passing through said sleeve, wedges on the sleeve adapted to frictionally engage with said flange, a retracting spring attached to the sleeve and to the frame, means operatively connected with the sleeve and with the valve of said motor for operating the valve, an air compressor, and an eccentric on said shaft for operating the air compressor.

3. In apparatus of the class specified, the combination of a frame, a motor thereon, a crank formed with a sleeve rotatively mounted on the frame and operatively connected with the piston of said motor, a shaft having a flange thereon and passing through said sleeve, wedges on the sleeve adapted to frictionally engage with said flange, a retracting spring attached to the sleeve and to the frame, means operatively connected with the sleeve and with the valve of said motor for operating the valve, an air compressor, an eccentric on said shaft for operating the air compressor, and means for controlling the operation of the air compressor by the eccentric.

4. The combination of a frame, a crank formed with a sleeve and rotatively mounted on the frame, said sleeve having curved inclined surfaces thereon, a shaft passing through the sleeve and having a flange thereon, wedges arranged on said surfaces, and means on the sleeve and wedges for moving the wedges on said surfaces to cause the wedges to make frictional contact with said flange.

5. The combination of a frame, a crank formed with a sleeve and rotatively mounted on the frame, said sleeve having curved inclined surfaces thereon, a shaft passing through the sleeve and having a flange thereon, wedges arranged on said surfaces, means on the sleeve and wedges for moving the wedges on said surfaces to cause the wedges to make frictional contact with said flange, and means including a pneumatic motor for operating said crank.

6. The combination of a frame, a crank formed with a sleeve and rotatively mounted on the frame, said sleeve having curved

inclined surfaces thereon, a shaft passing through the sleeve and having a flange thereon, wedges arranged on said surfaces, means on the sleeve and wedges for moving the wedges on said surfaces to cause the 70 wedges to make frictional contact with said flange, means including a pneumatic motor for operating said crank, and an air compressor operatively connected with said shaft.

7. The combination of a frame, a crank formed with a sleeve and rotatively mounted on the frame, said sleeve having curved inclined surfaces thereon, a shaft passing through the sleeve and having a flange 80 thereon, wedges arranged on said surfaces, means on the sleeve and wedges for moving the wedges on said surfaces to cause the wedges to make frictional contact with said flange, means including a pneumatic motor 85 for operating said crank, an air compressor operatively connected with said shaft, and means including a barostat for controlling the operation of said air compressor.

8. In apparatus of the class specified, the combination of a shaft, an eccentric thereon, an air compressor, including a cylinder and a piston arranged therein, a link operatively connecting the piston with said eccentric, a retracting spring connected with said piston, and means including a barostat for controlling the operation of said link by said eccentric.

9. In apparatus of the class specified, the combination of a shaft, an eccentric thereon, 100 means for compressing air, including a cylinder and a piston arranged therein, a link adapted to operatively connect the piston with the eccentric and having a projection thereon, a casing, and means actuated by 105 compressed air in said casing for controlling the operation of the link by said eccentric, including a spring-pressed bar carrying a hook adapted to fit over said projection, hollow disks in said casing, and a rod 110 operatively connected between said disks and said bar.

10. Apparatus of the class specified, comprising a frame, a pneumatic motor thereon, a crank formed with a sleeve rotatively 115 mounted on the frame and operatively connected with the piston of said motor, a shaft having a flange thereon and passing through said sleeve, wedges on said sleeve adapted to move outwardly to frictionally engage with said flange, a retracting spring attached to the sleeve and to the frame, means operatively connected with the sleeve and with the valve of said motor for operating the valve, an eccentric on said shaft, an air compressor mounted on the frame, including a cylinder and a piston arranged therein, a link operatively connecting the last mentioned piston with said eccentric, a retracting spring on the frame connected with the 125

last mentioned piston, and means including a barostat on the frame for controlling the operation of said link by said eccentric.

11. Apparatus of the class specified, comprising a frame, a pneumatic motor thereon, a crank formed with a sleeve rotatively mounted on the frame and operatively connected with the piston of said motor, a shaft having a flange thereon and passing through said sleeve, wedges on said sleeve adapted to move outwardly to frictionally engage with the flange, a retracting spring attached to the sleeve and to the frame, means operatively connected with the sleeve and with the valve of said motor for operating the valve, an eccentric on said shaft, means on the frame for compressing air, including a cylinder and a piston arranged therein, a link adapted to operatively connect the last mentioned piston with the eccentric and having a projection thereon, a casing on the frame, and means actuated by compressed air in said casing for controlling the operation of the link by the eccentric, including a spring-pressed bar carrying a hook adapted to fit over the projection, hollow disks arranged in said casing, and a rod operatively connected between said disks and said bar.

12. In apparatus of the class specified, the combination of a frame, a pneumatic motor thereon, a crank formed with a sleeve rotatively mounted on the frame and operatively connected with the piston of said motor, said sleeve having curved inclined surfaces thereon, a shaft having a flange thereon and passing through said sleeve, wedges arranged on said surfaces, means including a dog for holding said wedges from outward movement on the surfaces, and means on the sleeve and wedges for causing outward movement of the wedges on said surfaces to have said wedges frictionally engage with said flange.

13. In apparatus of the class specified, the combination of a frame, a pneumatic motor thereon, a crank formed with a sleeve rotatively mounted on the frame and operatively connected with the piston of said motor, said sleeve having curved inclined surfaces thereon, a shaft having a flange thereon and passing through said sleeve, wedges arranged on said surfaces, means including a

dog for holding said wedges from outward movement on the surfaces, means on the sleeve and wedges for causing outward movement of the wedges on said surfaces to have said wedges frictionally engage with said flange, and means including a stop on the frame adapted to move said wedges out of frictional engagement with said flange when said shaft is operated in a reverse direction.

14. The combination of a frame, a motor having a valve including an oscillatable member, a crank formed with a sleeve rotatively mounted on the frame and operatively connected with the piston of said motor, a shaft passing through the sleeve and having a flange thereon, wedges arranged on the sleeve and adapted to frictionally engage with said flange, a retracting spring connected to the sleeve and to the frame, a lever operatively connected with said oscillatable member, and means on said sleeve and lever for operating the lever.

15. The combination of a frame, a motor having a valve including an oscillatable member, a crank formed with a sleeve rotatively mounted on the frame and operatively connected with the piston of said motor, said sleeve having curved inclined surfaces thereon, wedges arranged on said surfaces, a shaft having a flange thereon and passing through said sleeve, means including a dog for holding said wedges from outward movement on the surfaces, means on the sleeve and wedges for moving the wedges outwardly on said surfaces to cause the wedges to make frictional contact with said flange, a retracting spring connected to the sleeve and to the frame, a lever operatively connected with said oscillatable member, and means on said sleeve and lever for operating the lever.

In testimony whereof, I have signed my name to this specification, in the presence of two subscribing witnesses, at Los Angeles, county of Los Angeles, State of California, this 5th day of March, A. D. 1914.

HARRY A. BROOKS.
